UNITED STATES PATENT OFFICE.

EMIL F. BUTTS, OF TACOMA, WASHINGTON, ASSIGNOR OF ONE-HALF TO EDWIN GREGORY, OF TACOMA, WASHINGTON.

SCROLL-SANDING MACHINE.

Application filed January 25, 1923. Serial No. 614,883.

To all whom it may concern:

Be it known that I, EMIL F. BUTTS, a citizen of the United States, and a resident of Tacoma, in the county of Pierce, State of Washington, have invented certain new and useful Improvements in Scroll-Sanding Machines, of which the following is a specification.

This invention relates to machines used in the manufacture of furniture, and kindred industries, for the purpose of smoothing the rough surface of curved and other specially shaped or molded wooden pieces after they have been brought to the desired rough shape and size in the other machinery.

The objects of the invention are to provide a machine which will brace the piece of wood while it is being manipulated to smooth its varying surfaces; to insure that the smoothed surface is finished at the correct angle with the adjacent surface; to permit the part being smoothed to be swung into any position in order to bring the surface into contact with the sanding belt; to permit the belt to be bent in order to smooth special shapes; which will greatly increase the speed at which this work may be done; and which is simple to operate.

I attain these and other objects by the devices mechanisms and arrangements illustrated in the accompanying drawings, in which—

Fig. 1 is a side elevation of my machine, showing the outline of a part of the top rail of a chair back being smoothed thereby; Fig. 2 is a front elevation thereof; showing the work brace board in vertical position and, in dotted lines, in tipped position to change the angle between its surface and the plane of the sanding belt; Fig. 3 is a plan thereof; Fig. 4 is a section of a part thereof, on the line 4—4 in Fig. 3, and Fig. 5 is a side elevation of the complete machine. Similar numerals of reference refer to similar parts throughout the several views.

This invention relates to that class of smoothing machines which use a traveling sand belt and is a special form of sanding table.

The base table 1 is suitably supported and is provided with two notches 2 and 3 which are cut in its front and rear edges respectively. These notches may preferably be made with slanting ends 4 and 5, respectively, as shown in Figs. 1 and 3 and are

intended to permit a part of the piece being worked on to swing to practically any angle relatively to the sanding belt, without striking the base table 1.

Two similar blocks 6 are adjustably mounted on top of the table 1, one on each side of the notches 2 and 3. Each block 6 has base flanges 7 formed on its front and rear sides, and these flanges 7 engage under the guides 8 which are secured to the top of the base table 1. The two blocks 6 are secured together by a special work table 9, and may be moved laterally under the guides 8 for the purpose of bringing the work table 9 to the desired position. The work table 9 is secured to the said blocks 6 by means of two bolts 10, whose heads are mounted in the countersunk slots 11 in the upper surfaces of the two blocks 6, said slots 11 extending from front to rear of said blocks 6. The nuts 12 of the bolts 10 are countersunk into the top of the work table 9 so as not to interfere with the sand belt passing thereon. The work table 9 may therefore be adjusted further forward or backward by loosening the nuts 12 on the bolts and sliding the table 9 and the bolts 10 into the said desired position. As seen in Fig. 3, the work table 9 is provided with a broad shallow notch 13 in its front edge, the part 14 forming the rear end thereof being slantingly undercut, as shown in Fig. 4. Also a correspondingly positioned notch 15 is formed in the rear edge of the work table 9. This notch 15 is as broad as the notch 13 but is much deeper and only leaves a narrow part 16 of the table 9 between it and the notch 13. The upper rear edge 17 of the part 16 is rounded as desired. Two lateral cuts or slots 18 extend from the two inner corners of the notch 15, parallel with the front edge of the table 9, the front sides of the said cuts 18 being a continuation of the rear edge 17 of the part 16, and are rounded to make a gradual change of shape from the level of the work table 9 to the rounded part 17. The sand belt 19 travels on top of the work table 9 over the part 16 thereof, and may extend slightly over the rounded part 17 as shown in Fig. 4. The particular dimensions of the part 16 and its curved part 17 depends on the work to be done in the machine, different tables being provided for different parts to be smoothed.

A collar or socket 20 is secured to the base

table 1 at a point towards the rear and to one side of the notch 3 therein. A column 21 is adjustably secured in vertical position in the collar 20, being held in adjusted position by the set screw 22. The column 21 may therefore be adjusted either vertically or angularly about the axis thereof. The column carries, at its upper end, a head 23, through which the horizontal bar 24 passes, and this bar is held in adjusted position therein by the set screw 25. The bar 24 extends towards the front and its front end is offset, as at 26, towards the notches 2 and 3. The front end of the bar carries the work brace board 27. Therefore, by means of the set screw 22 the brace board 27, may be adjusted in vertical height and in horizontal angular position, and, by means of the set screw 25, it may be adjusted towards the front or rear and may be tipped to take a different vertical angular position, as shown in dotted lines in Fig. 2. The board 27 should be shaped substantially as shown in Fig. 1, having a straight horizontal lower edge 28 held above the part 16 of the work table to permit the sand belt 19 to pass between the parts 16 and 28 (Fig. 4). Also a downward extending lobe 29 projects sharply from the front end of the straight part 28 and an opposite lobe 30 extends upward from the rear end of the said straight part 28. The upper edge of the board 27 is curved to make a convenient shape to brace the part being smoothed and to permit the operator's left arm to pass over it when the part thereof being held by the left hand is in or near the rear notch 3 in the base table 1. The brace board 27 is adjusted, as above described, in order to bring it into the desired position relatively to the traveling sand belt 19. Normally, of course, this position is at right angles to the belt but in certain cases the smoothed surface makes a different angle with the adjacent surface and in such cases the brace board must be adjusted to bring it to the desired new position.

The sand belt 19 used in this machine may be of any desired width but in practice I use narrow belts, from $\frac{3}{8}$ inch wide to 4 inches wide, according to the particular needs of the pieces being smoothed. As seen in Fig. 5 the sand belt 19 is mounted on the two wheels 31 and 32. The wheel 32 is driven by any suitable means as by the drive belt 33 and draws the sand belt 19 through the machine in such manner as to drag the piece being smoothed against the working surface of the brace board 27.

My improved scroll sanding machine is operated briefly in the following manner:— It is, of course, understood that the machine is intended for use in a factory where a large number of exactly similar pieces are to be smoothed in a lot. The proper work table 9 and belt 19 are therefore selected for

the lot to be worked on, and the table and brace board are adjusted to suit the work to be done. This lot usually consists of pieces from $\frac{1}{4}$ inch to 6 inches in thickness, such as chair back top rails, chair back banisters, buffet toilet frames, with differently shaped ornaments, and other similar parts. When the parts are very thin a number of them may be temporarily secured together in proper alignment and all smoothed together at the same time, thus reducing the time and the cost of production further. As indicated in Fig. 1, the outline of these pieces comprises straight portions combined with concave and convex portions. When the straight portion is to be smoothed it is held firmly down on that part of the sand belt traveling on the flat surface of the part 16 and is held against the brace board 27, the straight edge 28 of which engages the lower edge of the portion being smoothed adjacent to the sanding belt, and keeps it steady and straight while the belt is acting on it; similarly when the portion to be smoothed is rounded or convex in outline, the sharp corner at the beginning of the convex portion is first placed at the edge of the belt, the shape of the undercut part 14 of the table 16 permitting the belt to enter into the extreme corner, and then the portion is rolled on the belt (Fig. 1, dotted lines) being held firmly down thereon and thus the said convex part is smoothed. However, when the part to be smoothed is concave in profile, it is placed with the said concave portion pressing the rear edge of the sand belt 19 down over the rounded part 17 of the table 16 (Fig. 4), the belt gradually bending down to the required shape along the cut 18. Thus it will be seen that a scroll of any outline may be smoothed in this machine by manipulating it to bring its various surfaces successively on to the sanding belt, and that the brace board will steady it and will guide it so that it will not be forced out of the correct angle by the pull of the sand belt on the surface.

Having described my invention, what I claim is:—

1. In a scroll sanding machine, the combination of a traveling sand belt, having its abrasive surface upward; a work table whereon said belt travels, said table being notched in its front and rear edges to permit the portions of the scroll piece not being sanded to swing beyond the plane of the sand belt and thus permit the portion being sanded to be rolled on the said sand belt; and a work brace board supported over the traveling sand belt and adapted to brace and to guide the scroll piece held thereagainst and pressed on the sand belt.

2. An apparatus as set forth in claim 1, wherein the work table is adjustable relatively to the path of the belt, whereby the

edge of the table is brought to the edge of said belt.

3. An apparatus as set forth in claim 1, wherein the work table is notched in its front edge and is undercut to permit the scroll piece to be placed with the edge of the belt entering a reentrant scroll corner.

4. An apparatus as set forth in claim 1, wherein the work table is notched in its rear edge and the upper corner thus formed is rounded to permit the sand belt to be bent down thereover to smooth a concave portion of the scroll.

5. An apparatus as set forth in claim 1, wherein the work table is notched in its rear

edge and is provided with slot extensions to said notched part, the upper corner thus formed being rounded to permit the sand belt to be bent down thereover to smooth a concave portion of the scroll.

6. An apparatus as set forth in claim 1, wherein the work brace board comprises a low horizontal section positioned over the work table and separated therefrom by a space for the traveling sand belt, together with a downward extending front lobe and an upward extending rear lobe.

Signed at Tacoma, Wash., this 2nd day of August, 1922.

EMIL F. BUTTS.
